(57) **CLAIM**

The ornamental design for a dental capsule, as shown and described.

DESCRIPTION

FIG. 1 is a front view of a dental capsule that depicts my design;

FIG. 2 is a rear view thereof;

FIG. 3 is a top view thereof;

FIG. 4 is a bottom view thereof;

FIG. 5 is a right-side view thereof;

FIG. 6 is a right-rear-top perspective view thereof; and,

FIG. 7 is a left-side view thereof.

The broken lines shown in the figures depict portions of the dental capsule that form no part of the claimed design.

1 Claim, 2 Drawing Sheets
